UNITED STATES PATENT OFFICE

WILLIAM R. STOCKWELL, OF MICHIGAN CITY, INDIANA, ASSIGNOR TO WEIL-MCLAIN COMPANY, OF MICHIGAN CITY, INDIANA, A CORPORATION OF DELAWARE

BOILER

Application filed August 18, 1928. Serial No. 300,580.

This invention relates to improvements in boilers.

In boiler construction, and especially in connection with those of the rectangular type composed of a plurality of water sections, it is found highly desirable to encase the boiler proper in metal sheathing to hide unsightly portions such as the joints between the sections, and give the exterior of the boiler a symmetrical, rectangular shape, thereby adding greatly to the appearance of the same. The encasing sheathing is further employed to protect and cover the insulation commonly applied to the exterior of the boiler, in addition to holding the insulation in place. The artistic appearance of the boiler may also be further improved by finishing the metal sheathing in various colors.

A difficulty encountered in encasing boilers, and especially those of the sectional type, is to properly fit the casing to the boiler, because boilers of the same capacity vary in over-all size when finished, due to the sections not being uniformly fitted together. This is especially true of boilers wherein the sections thereof are placed one in back of the other and are connected by nipples, it being evident that boilers of the same capacity which have the sections tightly fitted together, are shorter from front to back than those which have the sections thereof more loosely fitted together.

One object of the invention is to provide encasing sheathing for boilers of the character indicated, which is constructed to compensate for variations in sizes of boilers of the same capacity, thereby accommodating the casing to all such boilers without modification or alteration.

A further object of the invention is to provide an encasing structure, for rectangular boilers of the sectional type, composed of a plurality of connected metal plates or sheets, wherein certain of the connecting portions provide an adjustable or expansion joint member whereby the casing will properly fit boilers of varying sizes.

Another object of the invention is to provide encasing sheathing means for boilers, which is designed to compensate for expansion and contraction of the boilers, thereby avoiding damage to the sheathing and joints thereof, ordinarily due to stretching of the walls of the casing.

Another object of the invention is to provide an encasing structure of simple design, which may be readily and economically applied to the boiler.

Yet another object of the invention is to provide an encasing sheathing structure for boilers wherein certain of the fittings of the boiler are employed to secure the sheathing in place, thus avoiding the use of additional securing means and greatly reducing the cost of encasing the boiler by economizing both in labor and material.

Other objects of the invention will more clearly appear from the description and claims hereinafter following.

In the drawings forming a part of this specification, Figure 1 is a top plan view of a square sectional type of boiler having my improvements embodied therein. Figure 2 is a front elevational view of the boiler illustrated in Figure 1. Figure 3 is a rear elevational view thereof. Figure 4 is a vertical longitudinal sectional view corresponding substantially to the line 4-4 of Figure 2. Figure 5 is a horizontal sectional view corresponding substantially to the line 5-5 of Figure 2. And Figure 6 is a vertical transverse sectional view corresponding substantially to the line 6-6 of Figure 1.

In said drawings, a construction of boiler is shown of that type comprising a plurality of tube sections A-A, clearly shown in Figures 4 and 5. The sections are of the vertical type and are disposed transversely of the boiler and placed one behind the other from front to rear thereof. The sections A are supported on a base 10 which comprises the usual front, rear and side walls defining a rectangular ash pit member. A grate 11 is supported on the base 10, immediately above the ash pit section. The ash pit door is indicated by 12 and is hinged to the front wall of the base 10. The clinker door 13 is disposed immediately above the ash pit door in an upward extension 14 provided on the base 10.

The boiler is provided with a governor 15.

located at the top thereof and having the usual lever mechanism 16 for controlling the operation of the check draft and draft door of the boiler, chains 17 and 18 being secured to opposite ends of the lever for this purpose. The chain 17 has the lower end thereof connected with a pivoted door 19 mounted on the right-hand side wall of the boiler, as shown in Figure 2, the door 19 regulating the admission of air to the ash pit of the boiler so as to control the draft. The chain 18 is connected to a check draft 20 which is mounted on the hood member 21 secured to the rear wall of the boiler and communicating with the usual flue pipe 22 leading to the chimney. The boiler is provided with the usual outlet pipes 23—23 which communicate with the heating radiators and extend from the top wall of the boiler. The return pipes are indicated by 24 and communicate with the bottom of the boiler through the rear wall thereof, as clearly illustrated in Figure 3. The boiler is also provided with the usual water gauge 25 mounted on one of the side walls thereof. In addition to the governor 15, the top of the boiler has a relief valve, a thermometer and an altitude gauge mounted thereon, the altitude gauge being designated by 27 and the pipe fittings leading to the thermometer and the relief valve being respectively designated by 28 and 29.

The boiler proper is enclosed within the ensheathing casing composed of a plurality of plates or sheets which are held to the boiler without the use of additional securing means, the same being clamped to the front and rear walls of the boiler by the usual fittings employed.

The ensheathing casing which encloses the boiler is composed of a front wall 30, a back wall 31, side walls 32 and 33 and a top wall 34. The front wall 30 comprises a single sheet or plate member which is cut away centrally at the bottom to correspond with the upward extension 14 of the front wall of the base casting 10, the opening provided in the sheet being of smaller size than the extension 14 so that the edge of the plate about said opening will be overlapped by the side and top edge portions of the extension 14. As most clearly shown in Figure 4, the bottom edge of the plate 30 is seated on the top portion of the front wall of the base casting 10 and is overlapped by the upper edge thereof, as indicated by the dotted lines in Figure 2 and as shown in the sectional view of Figure 4. The top edge portion of the plate 30 is provided with an inturned flange 35 connected to the body portion of the plate by a horizontal section 36. The side edges of the plate 30 are provided with similar flanges 35 and connecting portions 36. The plate 30 is provided with openings 37, 38, 39—39, to accommodate certain of the boiler fittings. The opening 37 is employed

to accommodate the flue cleanout door frame casting 40 which is secured to the front of the boiler and has the usual flue cleanout doors hinged thereto. The opening 37 is of slightly smaller size than the door frame structure 40 so that the flanged edge portion of the casting 40 will overlap the plate 30 at said opening to clamp the plate against the front wall of the boiler and hold the same in place. The door frame casting 40 is secured to the front wall of the boiler in the usual manner, either rivets, bolts or other securing means being employed.

The opening 38 is provided to accommodate the door frame casting 42 which carries the hinged fuel feed door of the boiler. The casting 42 is affixed to the front wall of the boiler in the usual manner by rivets or other means, and the opening 38 is of smaller size than the frame 42 so that the frame edge will overlap the plate 30 at said opening, thereby further clamping the plate to the front wall of the boiler. The openings 39 are three in number and are provided to permit access to plugs 43—43 which are employed to close certain openings in the front wall of the boiler. The openings 39 are of slightly larger size than the plugs 43 so that the latter may be readily applied and removed.

Both of the side walls 32 and 33 are in the form of plate members, each preferably comprising a single plate. Both of these walls are of similar design, each being provided with vertically extending right angular flanges 44—44 at the front and rear edges thereof. The bottom edge of each plate 32 and 33 rests on the base casting 10, as most clearly shown in Figure 6, the base casting being provided with a groove in which the bottom edge of said side wall is seated. The top edge of each side wall 32 and 33 is provided with a right angular inturned flange 45 for a purpose hereinafter pointed out. As most clearly illustrated in Figure 5, the flanges 44 at the front edges of the plates 32 and 33 engage within the grooves formed between the vertical flanges 35 of the plate 30 and the body portion proper of the plate. As will be evident, the side plates 32 are thus held in assembled relation with the front plate 30 by the interengaging flange sections thereof. The side plate 32 is provided with proper openings to accommodate the pipe connections for the valve members of the water gauge 25 and the plate 33 is provided with similar openings to accommodate the pipe connections of the blow-off cocks 26 at the other side of the boiler. The openings in the plates extend through the edges thereof so that the plates may be placed in position by slipping the same over the pipe fittings without detaching the latter.

The back wall 31 of the casing is composed of a pair of plate or sheet members which are vertically arranged side by side, as most

clearly illustrated in Figures 3 and 5. The joint between the two plate members of the wall 31 is formed by providing one of the plates with an offset edge section 46 overlapping the adjacent edge of the other plate, thereby forming in effect a lap seam. The opposite vertical side edges and the top edge of the plates forming the back wall 31 are provided with inturned flanges 47-47 connected to the wall proper by sections 48-48, the flanges 47 and connecting sections 48 being similar to the flanges 35 and connecting sections 36 of the front plate 30, hereinbefore described. The flanges 47 engage over the outstanding flanges 44 at the rear edges of the plates 32 and 33, thereby locking the side walls to the back wall of the encasing sheathing. The back wall section 31 is provided with a relatively large opening 49 adjacent the top thereof to accommodate the hood member 21, the opening 49 being of smaller diameter than the flange of the hood member so that the flange overlaps the wall 31 and said opening, thereby clamping the same to the back of the boiler. It will be understood that the hood casting 31 is secured to the boiler in the usual manner by rivets, bolts or other securing means. Adjacent the bottom edge, the back wall 31 is provided with a pair of openings 50-50, which accommodate the two return pipes 24 of the heating system, the openings 50 being in the form of slots so that the plates forming the back wall may be slipped over the return pipes. The back wall of the boiler is also provided with the usual openings for the hot water heating coil pipes, the openings in the back wall being closed by cover plates 51-51 secured in the usual manner. The plates forming the back wall section of the casing are provided with a pair of openings 52-52 registering with the coil pipe openings 50 but of smaller size than the cover plates for said openings, whereby the cover plates overlap the wall 31 adjacent said openings to further clamp the same to the boiler. The back wall of the boiler is usually also provided with an opening which is closed by a plug 53. The wall member 31 is provided with an opening registering with the plug 53 and of such a size as to freely permit application and removal of said plug.

The top wall 34 is composed of two plate members joined by a lap seam 54 which is in all respects similar to the lap seam 46 employed in connection with the back wall 31. The front and rear edges of the wall section 34 are provided with upstanding flanges 55-55 which engage between the flange 35 and the main body portion of the front wall 30 and the flange 47 and the main body portion of the back wall 31 of the casing. The top wall section 34 is thus secured to the front and back walls of the casing. The side edges of the wall section 34 are turned down-

wardly, as indicated by 56 in Figure 6, the downturned sections being overlapped by the top portions of the side walls 32 and 33 and the inturned flange sections 45 of the side walls engage over the horizontal edge sections of the top wall 34. The top wall is also provided with suitable openings 57-57 and 58-58, the openings 57 being two in number and accommodating the outlet pipes 23 of the boiler. The openings 58 are four in number and, as shown, accommodate the pipe fittings for the thermometer, altitude gauge, relief valve and governor or regulator of the boiler. The openings 57 and 58 open through the edges of the plates forming the top wall 34, as clearly shown in Figure 1, so as to facilitate the assembling of the parts. As will be evident, the top wall 34 of the encasing structure is held against displacement by the interengaging flanges of said wall and the front and rear walls and is further held against lateral displacement by the abutting sections of the side walls. The side walls, in turn, are held against displacement by the flanges thereof which engage with the flanges of the front and rear walls and the overhanging top flanges of the side walls serve to hold the top wall against upward displacement. As hereinbefore pointed out, the front and rear wall members 30 and 31 are securely clamped to the corresponding walls of the boiler by the door frames 40 and 42 at the front of the boiler and the hood casting 21 and cover plates 51 associated with the back wall of the boiler. It will thus be evident that the entire casing structure is held together without the employment of any securing means such as rivets or bolts, and that the entire casing is held to the boiler directly by the fittings usually employed in connection with the boiler, without the use of any additional securing elements. The cost of material is thus greatly reduced and, further, the labor necessary in assembling the parts is a great deal less than when the plates forming the casing are secured together by seaming or other securing operations.

In applying the casing to the boiler, the front plate 30 is preferably first placed in position and the flanged edge section of the top wall 34 engaged with the flange of the plate 30. The side plates 32 and 33 are next applied and the flanges thereof engaged with the flange of the plate 30 by slightly tilting the plates 32 and 33. After the flanges have been engaged, the side plates are forced into position against the sides of the boiler thereby engaging the overhanging top flanges over the top wall 34. The back wall 31, composed of the two plates, is next applied, the plates being applied separately so as to engage the flanges thereof over the flanges of the top wall 34 and side walls 32 and 33.

After the flanges have been interengaged, 130

the plates forming the back wall are forced together edgewise, to overlap the offset edge 46 with the adjacent edge of the other plate. The hood 21 and the cover plate 51 are then secured in position, thereby clamping the back wall in place. The door frames 40 and 42 are also secured in position to clamp the front wall 31 to the boiler. As will be evident, when the parts of the encasing structure have been thus assembled, the same will neatly fit the boiler and due to the play between the engaging flanges of the plates, the casing will accommodate itself to the boilers independently of unavoidable variations in sizes of boilers. In this connection, it is pointed out that variations in sizes of boilers of the same capacity, of the sectional type wherein the sections are placed one in back of the other, is unavoidable because in clamping or forcing the sections together, some of the sections will be fitted together more tightly than others, thereby varying the spacing between the sections; further, often all of the sections of one boiler are fitted together more loosely than the sections of another boiler of the same capacity, thereby increasing the over-all length, from front to rear, of the first named boiler over that of the latter.

As will be evident, in addition to compensating for variations in sizes of boilers, my improved encasing structure will also accommodate itself to the expansion and contraction of boilers due to changes in temperature, thereby avoiding damage to the joints between the sheets due to stretching of the casing.

Although in the present instance, the ensheathing casing is shown as directly covering the boiler proper, it will be appreciated that it is within the invention to provide the exterior of the boiler with insulating material and apply the ensheathing casing so as to embrace the insulating material to hold the same in position and also protect it against damage.

I have herein shown and described what I now consider the preferred manner of carrying out my invention, but the same is merely illustrative and I contemplate all changes and modifications that come within the scope of the claim appended hereto.

I claim:

In combination, a boiler of substantially rectangular shape; and a casing enclosing said boiler, said casing including a one piece front plate, a rear plate, a pair of one piece side plates, and a two piece top plate, said front and rear plates having inturned vertical edge portions at opposite sides thereof overlying said side plates and confining the same, said front and rear plates having in-turned top flanges overlying the front and rear edges of the top plate to confine said plate, said top plate having the front and

rear edges abutting the front and rear plates to confine the same therebetween, the two pieces of said top plate having overlapping edge portions, said pieces of the top plate having the outer side edges thereof downturned, 70 said downturned edges engaging said side plates, whereby the top plate is held thereby against lateral shift, said front and rear plates being clamped to the front and rear ends of the boiler, respectively.

In witness that I claim the foregoing I have hereunto subscribed my name this 8th day of August, 1928.

WILLIAM R. STOCKWELL.
